US00D720853S

(12) **United States Design Patent**
Dominik et al.

(10) **Patent No.:** **US D720,853 S**
(45) **Date of Patent:** **** Jan. 6, 2015**

(54) **FIXATION CLAMP**

(75) Inventors: **Robert Dominik**, Lausanne (CH); **Klaus Dorawa**, Safnern (CH); **Adam Busch**, Olten (CH)

(73) Assignee: **Stryker Trauma SA** (CH)

(**) Term: **14 Years**

(21) Appl. No.: **29/394,189**

(22) Filed: **Jun. 14, 2011**

(30) **Foreign Application Priority Data**

Dec. 14, 2010 (WO) 577932301

(51) **LOC (10) Cl.** **24-02**

(52) **U.S. Cl.**

USPC **D24/155**

(57) **CLAIM**

The ornamental design for the fixation clamp, as shown and described.

DESCRIPTION

FIG. 1 is a perspective view of a fixation clamp, in accordance with one embodiment of the present invention; and, FIG. 2 is a side view of the fixation clamp shown in FIG. 1. Portions of the fixation clamp shown in the drawings in phantom lines constitute no part of the claimed design.

1 Claim, 2 Drawing Sheets
